UNITED STATES PATENT OFFICE.

QUINCY BENT, OF LEBANON, PENNSYLVANIA.

CONCENTRATOR.

No. 815,673.

Specification of Letters Patent.

Patented March 20, 1906.

Application filed April 14, 1904. Serial No. 203,164.

To all whom it may concern:

Be it known that I, QUINCY BENT, a citizen of the United States, residing at Lebanon, in the county of Lebanon, State of Pennsylvania, have invented certain new and useful Improvements in Concentrators, of which the following is a full, clear, and exact description, reference being had to the accompanying drawings, of which—

10 Figure 1 is a plan view. Fig. 2 is a longitudinal section on line x x , Fig. 1. Fig. 3 is an end elevation enlarged. Fig. 4 is a sectional detail of a portion of the table and magnets, enlarged. Fig. 5 is a diagrammatic illustration of the electrical connections. Fig. 15 6 is a detail of the switch or commutator for causing the demagnetization and remagnetization of the magnets.

This invention has for its object the production of an improved means and apparatus for separating magnetizable particles in ores, such as iron ores or other suitable material, from the non-magnetizable particles.

The invention comprises, in combination, 25 a suitable table, a series of electromagnets, means for imparting reciprocatory movements to the latter, means for demagnetizing the magnets at or near the end of their stroke in one direction, and means tending to carry 30 off the material upon the table in a direction transverse to that of the movements of said magnets, the construction being such as hereinafter described, whereby the magnetizable particles of ore suitably deposited on said 35 table are caused to be carried across the same, partly by the influence of the magnets and partly by momentum, by a step-by-step movement, the magnetizable particles being thereby separated from the non-magnetizable 40 particles in passing through the apparatus.

The invention also comprises certain novel features and combinations hereinafter particularly described and pointed out.

45 In the preferred form of the invention, which is that shown in the accompanying drawings, I make use of the reciprocating table of an ore-concentrator of well-known construction. Referring to the drawings, 1 is the inclined table of said concentrator, which is slidable lengthwise in suitable guideways of a supporting-frame 2 and is adapted to be reciprocated by means of a driven rotatable shaft 3, carrying an eccentric 4, that is connected by a rod 5 with an arm 6, depending from the table, there being an open spiral

spring 7 on said rod to the rear of arm 6, one end of which spring bears against the latter and its other end against a collar 8 on the rod. This rod passes through a hole in arm 6, and there is a spring 9 of less resistance or power than the spring 7 upon the projecting end of the rod, one end of which spring 9 bears against said arm 6 and the other end against a collar 10 on the rod. Along the upper or high edge of the table 1 are sprinklers 11 with which connect pipes 12, that communicate with a source of water-supply. When the apparatus is in operation, the ore or ore-pulp is continually deposited upon the table near the rear upper corner thereof and the water is allowed to flow through the sprinklers down over the table. The manner of operation of the said apparatus is well known, the material being carried forward by each forward reciprocation of the table and the heavier of the particles thrown farther forward through their momentum by the sudden bump of the table occurring at the end of the stroke of the rod 5. The heavier the particles the farther they are thrown.

In carrying out my invention I secure to the under side of the table 1 a series or row of electromagnets 13, the first of which is at a point below the place—the upper rear corner A of the table—where the ore-pulp or other material to be treated is deposited. The upper poles of the magnets are adjacent to the surface of the table, and their lower poles are preferably connected by a bar 14, that is secured to the table and holds the magnets in place. There is a commutator 15 of well-known construction upon the shaft 3, which commutator is suitably connected by conductor-wires (not shown) with the magnets 13 and with a source of electrical energy. This commutator is adapted to cause the demagnetization of the magnets at the end of the forward stroke of the table, or, rather, in this instance, a short time before the end of the stroke, preferably when the table has made about four-fifths of its full forward stroke. Otherwise stated, the current is allowed to be on during, say, forty per cent. of each revolution of the shaft 3 and the commutator and eighty per cent. of the forward movement of the table.

The mode of operation of the apparatus is as follows: The ore-pulp deposited upon the table at A, descending by gravity, comes into the field of attraction of the first magnet of

the series. At the forward reciprocation of the table the magnetizable particles of the ore, held by attraction of the magnet, are carried along positively until they suddenly cease to be attracted—that is, until the commutator causes the demagnetization of the magnet—whereupon the immediate stopping and jolt of the table just prior to the beginning of the return movement causes the released ore particles to move forward as projectiles by their momentum into what in a moment becomes the field of attraction of the next or second magnet—that is, when the table has reached the end of its return stroke. On the next forward movement of the table these particles will be carried forward by the last-mentioned magnet and in like manner into the field of attraction of the third magnet, and so on from one magnet to the next until they leave the last magnet of the series (when the latter is demagnetized) and descending the table are allowed to fall into a suitable receptacle. The silicious or earthy and other non-magnetizable matter is washed down and off the table by the body of water flowing from the sprinklers. In order to catch the magnetizable particles that may not happen to be caught or held by the said series of magnets, I would sometimes employ a second row or series of like magnets (marked 13^a) below the first series, as seen in Fig. 3 and indicated by dotted lines in Fig. 1, the magnets of said second series alternating with those of the first series, as indicated in Fig. 1. If necessary, there may be another like alternating series of magnets below the preceding ones.

A body of water flowing over the table may be dispensed with and gravity alone be relied upon to carry the separated ore from the table.

Other modifications of the apparatus may be employed in carrying out the invention without departing from the essential principles thereof—to wit, the separation of the magnetizable particles of ore by the successive magnetization and demagnetization of a series of reciprocating magnets and the momentum of said particles upon the sudden release thereof from the control of the magnets upon the demagnetization thereof.

Having thus described my invention, I claim as new and desire to secure by Letters Patent—

1. In a magnetic separator, the combination of a support for the material to be treated, a magnet, means for imparting reciprocatory movement to said magnet, means for demagnetizing said magnet at or near the end of its stroke in one direction, and means tending to carry off the material deposited on the support in a direction transverse to that of the movement of said magnet, whereby the magnetizable particles of material deposited on said support are caused to be transported

across said support partially by being carried by said magnet in its forward stroke, and partially by momentum after being released therefrom, substantially as set forth.

2. In a magnetic separator, the combination of a support for the material to be treated, a magnet adjacent thereto, a second magnet below the first magnet and in advance of the latter, means for imparting simultaneous reciprocations thereto, means for simultaneously demagnetizing said magnets at or near the end of their stroke in one direction, together with means tending to carry off material deposited upon said support in a direction transverse to that of the movement of said magnets, substantially as set forth.

3. In an ore-separating apparatus, the combination of a suitable table, a series of electromagnets, means for imparting simultaneous thereto reciprocatory movements, means for demagnetization of said magnets at or near the end of their stroke in one direction and means tending to carry off the material deposited on the table in a direction transverse to that of the movement of said magnets, whereby the magnetizable particles of material deposited on said table are caused to be transported across said table by a succession of impulses, substantially as set forth.

4. In an ore-separating apparatus, the combination of a table, a series of electromagnets adjacent to the surface thereof, means for imparting simultaneous reciprocations thereto, a second series of similar magnets below the first series and alternating with the latter, and means for simultaneously demagnetizing said series of magnets at or near the end of their stroke or movement in one direction, substantially as and for the purpose set forth.

5. In an ore-separating apparatus, the combination of an inclined table, a series of electromagnets movable therewith, means for imparting lengthwise reciprocatory movements to said table, and means for demagnetizing said magnets at or near the end of the stroke in one direction thereof, together with means for causing water to flow transversely over and upon the top of said table, the construction being such that the magnetizable particles of material deposited on said table will be transported across the latter athwart the water by a step-by-step movement, partly by influence of said magnets and partly by momentum, substantially as set forth.

In testimony whereof I have hereunto affixed my signature this 20th day of February, A. D. 1904.

QUINCY BENT.
